ROTARY INKING MECHANISM

Charles Alonzo Harless, Oak Park, Ill., assignor
to The Goss Printing Press Company, Chicago,
Ill., a corporation of Illinois

Application December 13, 1938, Serial No. 245,363

21 Claims. (Cl. 101—350)

The invention relates to new and useful improvements in inking mechanisms for rotary printing presses, and more especially to such improvements in the ductor roller actuating and governing mechanism in rotary presses capacitated to print in a single color and in multi-color.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is an elevation of a mechanism embodying the invention as adapted to a press printing in a single color;

Fig. 2 is a section on line 2—2 of Fig. 1;

Fig. 3 is a section on line 3—3 of Fig. 1;

Fig. 4 is a detached detail of a dwell regulating device shown at the upper left hand in Fig. 1;

Fig. 5 is a section on line 5—5 of Fig. 1;

Fig. 6 is a section on line 6—6 of Fig. 1;

Fig. 7 is an elevation of a mechanism embodying the invention and adapted to a press printing in one color or a plurality of colors;

Fig. 7—A is a view taken on line 7a—7a of Fig. 7;

Fig. 8 is a section on line 8—8 of Fig. 7;

Figs. 9 to 12 are detached detail views of the various interacting levers shown in Figs. 7 and 7—A; and

Fig. 13 is a section on line 13—13 of Fig. 7.

Objects of the invention are to provide a novel and useful inking mechanism for fast running rotary printing presses which has simple, sturdy and reliable means for operating, and for nicely and reliably regulating the travel of a ductor roller and its coaction, respectively, with a fountain roller and an ink drum or the like; to provide for exact regulation and variation, over a relatively wide range, in the dwell of the ductor at the fountain roller; to provide very simple and exact means for effecting said regulation; to provide such mechanism and such exact control and regulation for ductor rollers of varying size; to provide such mechanism and control capacitated for use in presses having a plurality of ink foun-

tains, for instance, in presses adapted to printing either in a single color or in multi-color; to provide in such a machine a nice control and regulation required for printing in one color and also a different control and regulation required for color printing.

With these and other objects in view, the present preferred embodiment, illustrated herewith, comprises a ductor roller actuating shaft having radially-extending arms in which the ductor roller is rotatably mounted. The ductor roller governing and actuating mechanism comprises two angled, side-by-side actuating levers loosely mounted on said ductor roller shaft, these levers having cam rollers mounted in their inner ends, respectively, in side-by-side relationship, the cam rollers cooperating with two side-by-side rotating cams fixed on the fountain roller shaft. One of these cams and its lever mechanism effects and governs the travel of the ductor roller between the fountain roller and ink drum and its dwell there, and the other cam and its lever mechanism regulates the dwell of the ductor roller at the fountain roller. Means are provided for varying and regulating the angular relation or position of the two angled, cam-actuated levers, both with respect to each other and to the ductor roller shaft, such means being located at the outer and spaced apart ends of the levers. For this purpose, a regulating arm is keyed to the ductor roller shaft, and in the outer end of this arm there is mounted a rod which is longitudinally stationary but is rotatable and has screw-threaded engagement with nuts which are pivotally mounted in said outer, free ends of the two angled levers. By rotating the screw-threaded rod, the two actuating levers are moved concurrently either toward or away from each other, and the angular relation of the two levers with respect to each other and to the ductor roller shaft may be varied to adapt and adjust the system for ductor rollers of different diameters. For the purpose of varying the dwell of the ductor roller at the fountain roller there is further individual, screw-threaded adjustment between the previously described screw rod and the free end of the actuating lever carrying the dwell-determining cam roller which is independent of or in addition to the concurrent regulation of the two actuating levers previously described. In the embodied adaptation of the invention to a press having a plurality of ink fountains, and capacitated to print in one color or in another color, two ink fountains and two fountain rollers and two ductor rollers for alternative use are provided in a well-known

manner, and a single system of actuating and regulating levers for the ductor roller of the character described are provided, capacitated to afford the varied regulation requisite for these two different kinds of printing. A spring acts to impel the lever system, the shaft and ductor roller toward the fountain roller, the actual movement, however, being under control of the cams. It will be understood that the foregoing general description, and the following detailed description as well, are exemplary and explanatory of the invention, but are not restrictive thereof.

Referring now to the embodiment of the invention illustrated by way of example in the accompanying drawings, there is shown in Figs. 1 to 6 a mechanism employing a single ink fountain and ductor roller such as is especially capacitated for the inking mechanism of a one color rotary press. As embodied, an ink fountain 1 in which rotates a fountain roller 2, is mounted on a shaft 6, the shaft being journaled in the fountain side walls or in the press frame. These may be of any known or suitable form and will be provided with driving means and with ink-regulating devices in a well-known manner. A suitable ink-receiving member such as a drum 3, likewise suitably driven is provided, and these are journaled in the press frame 4 in a well-known manner. A ductor roller 5 is mounted to oscillate or move to and fro between the fountain roller 2 and the ink drum 3, and as shown is rotatably mounted in the outer ends of a pair of arms 11, which are keyed at 10 on a shaft 12, journaled in the press side frames 4.

Means are provided by the invention for accurately regulating and fixing the coaction of the ductor roll with the ink drum and with the fountain roller, and for regulating and fixing each of these functions independently of the other, said means being incorporated with the ductor roller actuating mechanism. In the illustrative embodiment of Figs. 1 to 6, two side-by-side cams 16 and 17 are shown separately mounted and fixed on the exterior end of the fountain roller shaft 6, these cams having different tracks, operating in the manner and for the respective purposes hereinafter explained. Actuated and controlled by these cams, respectively, are two side-by-side levers, which are mounted concentrically with the ductor roller shaft 12. These levers are independently relatively movable, one lever (34) governing the coaction of the ductor roller and ink drum, and the other lever (21) governing the dwell of the ductor roller on the fountain roller. The lever 34 is acutely angled and lever 21 is obtusely angled; at their adjacent ends they cooperate, respectively, with the side-by-side cams 16 and 17, while interposed between and connected to their other and spaced apart ends are screw-threaded positioning devices, which devices are mounted in fixed angular relation to shaft 12, on which the ductor roller 5 is mounted and about which it swings. Cooperating with the cam 17 is a roller 18, rotatably mounted on a pin 19 carried in the inner end 20 of the angled actuating or rocking lever 21. Lever 21 has a median hub 22, concentric with shaft 12, and for convenience is loosely journaled on hub 23 of an arm 24, which arm is fixed by a key 25, to 70 rotate with the shaft 12. Arm 24, being fixed to the shaft 12, is in fixed position relative to the ductor roller, and serves as a regulating and positioning arm for the actuating levers which are angularly movable on said shaft for the purpose 75 of varying and controlling the movement of the

ductor roller. Cooperating with the cam 16 is a cam roller 31 rotatably mounted in the inner end of the other angled actuating or rocking lever 34. This lever has a median hub 35 journaled on the shaft 12 beside and just within the hub 23 of the arm 24, previously described.

Referring now to the embodied means for variably angularly positioning and maintaining the two bent actuating levers 21 and 34 in fixed angular relation with respect to each other and to the ductor roller shaft 12, the arm 24 is fixed to shaft 12, and so is in fixed angular relation to the ductor roller 5 and its carrying arms 11, and an outwardly extending supporting block 39 is fixed to the outer end of the arm 24 by means of bolts 40 and 41 (Figs. 1 and 3). A screw-threaded rod 46 is rotatably mounted on block 39 and has threaded engagement with the outer, spaced apart ends of arms 60 and 54 of bent levers 21 and 34. To support screw rod 46, there is pivotally mounted in the outer end of block 39 a stub shaft 43, integral with which is a head 45 having a cylindrical seat, in which is rotatably mounted the screw-threaded positioning rod 46. Rod 46 is held from longitudinal movement by 25 collars 47 and 48 abutting on either side of the head 45. The collar 48 is provided with apertures for the insertion of a turning tool. One end of the positioning rod 46 has a screw-thread 51, threaded into a head 52, which head is pivotally mounted by a stub shaft 53 in the outer end of the arm 54 of the actuating lever 34. The opposite end of rod 46 has a screw-thread 57, threaded into the interior of a bushing 58, which is rotatably mounted in a head 59, said head having integral therewith a stub shaft 61, rotatably mounted in the outer end 62 of said arm 60 of the actuating lever 21. By turning rod 46, the ends of arms 60 and 54 of the two bent levers 34 and 21 may be moved nearer together or farther apart, and also relatively to arm 24 and the ductor roller 5 and its arms 11. Means are provided for firmly clamping lever 21 to arm 24 in any angular position to which the levers are brought by the screw rod 46. Accordingly a screw 45 bolt 63 extends through a bearing washer 64 and an aperture 63a in arm 24 (Figs. 1 and 6) and is screw threaded into arm 54 of lever 34 and clamps the lever 34 and arm 24 firmly in position and prevents undue strain on the rod 46 and associated parts.

Means are also provided, in accordance with one feature of the invention for varying the angular position of actuating lever 21 relatively to arm 24 and the ductor roller while leaving the lever 34 undisturbed; that is, lever 21 is moved angularly relatively to the other actuating lever and to shaft 12, but the relation of the lever 34 is undisturbed. Accordingly, a hand wheel 65 has a centrally apertured, tubular hub 66 fitting over the outer end of the bushing 58 and fixed thereto by a clamping screw 67. On the inner side of the head 59 the bushing has an annular flange 68. By turning the hand wheel 65, the lever 21 may be moved angularly without disturbing the lever 34, and thus the time and point of the engagement of lever 21 with cam 17, and the period of dwell of the ductor roller at the fountain roller may be varied and determined as desired. Means are provided for clamping the rod 46 and bushing 58 in position, and as embodied the head 59 is split on its outer side as shown at 70, and a threaded bolt 71 passes through both of the split parts and is pinned to the lower part at 72. A nut 73 is screw-threaded 75

onto the bolt 71, and is preferably provided with a handle 74. The hand wheel 65 is preferably provided with an annular scale 76 with which cooperates a pointer 77 mounted on the head 59, which serve as an indicator in effecting nice adjustment of the dwell. Resiliently acting means are provided impelling the ductor roller and its system of actuating levers toward the fountain roller, the resulting movement being under the control of the cams 16 and 17 on the fountain roller shaft. For this purpose a tension spring 79 has one end fastened to an extension of arm 24 and the other end fastened to the press frame. This spring acts continuously to hold rollers 31 and 18 to their cams.

The manner of operation of the precedingly described mechanism is substantially as follows: When the press is running, the ink distributing drum 3 and the fountain roller 2 are driven from the press in any suitable manner, and the supply of ink to the fountain roller from the fountain is governed by suitable devices, not shown. The cam rollers 31 and 18 are yieldingly held by spring 79 to the corresponding cams 16 and 17, which cams rotate together, to effect and govern the action of the ductor roller 5. Considering the ductor roller 5 at the fountain roller, at the proper time cam 16 swings lever 34 counterclockwise, and with it the entire lever system (due to the connection through screw rod 46) and thereby the cam 16 brings the ductor roller 5 against the ink drum, and controls the period of dwell of the ductor roller on the ink drum. As the cam 16 continues to rotate, the ductor roller is carried away from the ink drum 3 as lever 34 follows cam 16 under the impulsion of spring 79. At a predetermined point, and before the ductor roller 5 touches the fountain roller 2, the control of the lever system, and therewith of the ductor roller 5, passes to lever 21 and the cam 16, which controls the amount of dwell of the ductor roller on the fountain roller. At the close of the predetermined period of dwell at the fountain roller, the ductor roller is moved in the opposite direction against the action of the spring 79, and cam 16 again engages with cam roller 31 of lever 34 and moves the ductor roller again into engagement with the ink drum 3. The dwell of the ductor roller 5 at the ink drum 3 is determined by the conformation of the cam 16 and the angular set of lever 21 and may be varied through a wide range from a suitable minimum to a suitable maximum. The period of dwell of the ductor roller on the fountain roller is regulated by turning the hand wheel 65, which changes the angular position of the lever 21 alone (as previously described), and thus changes the relative position of the cam roller 18 relatively to the cam roller 31 angularly about the pivotal centers of their levers, which determines the point at which the control of the lever system passes from one cam to the other, and also determines both the time and the extent of arc during which the ductor roller engages with the fountain roller, thereby to vary the dwell desired. The magnitude of the angle between the ductor roller arms and both cam actuated levers may be varied as desired, and this is effected by concurrently, equally and oppositely varying the angular position of both levers 21 and 34 relatively to the arm 24, which is keyed to the shaft 12, to which the ductor roller arms are also keyed. This is effected by turning the screw-threaded rod 46 in either direction as required, and thereupon the relative position of the cam rollers 18 and

31 are concurrently varied angularly with respect to their cams 17 and 16 in equal amount but in opposite directions. This varies the amount of arcuate movement of the entire lever system and provides adjustment for ductor rollers of different diameters. With a ductor roller of given size the system is set to effect proper contact with the ink drum and proper dwell on the ink fountain roller. Should a ductor roller of different diameter be substituted, when the latter roller is set to the same contact with the ink drum as had the first roller, then the new ductor will have the same contact and time of contact on the fountain roller as had the former ductor roller.

Referring now to the embodied form of mechanism adapted for a press having a plurality of inking fountains, for instance, a press designed to print either in one color or in multi-color, that is, a press having two alternately usable ink fountains, fountain rollers and ductor rollers, as exemplarily shown in Figs. 7 to 13, certain parts which are the same in both of the illustrated forms, and have been previously described and designated, are indicated by the same reference numerals in Figs. 7 to 13, and will not be further described. In this form the one fountain roller is indicated by 2 and the other fountain roller by 2^a, and one ductor roller by 5 and the other ductor roller by 5^a. The arms 11 of the ductor roller 5 and the arms 11^a of the ductor roller 5^a may be integral and be keyed to the shaft 12 at 10 as already described. Only one of the ductor rollers 5 or 5^a is mounted in the mechanism at any one time, dependent on whether the press is running in one color or the other. Referring now to Figs. 7 to 13 in further detail, an outer lever 84 has a hub 85 loosely mounted on the hub 86 of a central arm 87, which is keyed to the shaft 12 at 25. This arm 87 corresponds to the arm 24 previously described, and is keyed in fixed angular relation to the shaft 12 and carries the rotatable screw rod 46, and associated parts that control the angular position of the other levers to vary and regulate the amplitude of vibration on the ductor roller. With this form of mechanism it is necessary to change the direction of pull of the spring 79 which impels the ductor roller toward the fountain roller, under control of the cams, from one side to the other of shaft 12. For this purpose the spring is selectively settable, and accordingly two arms 93 and 94 are formed integral with and extend outwardly on opposite sides from the hub 86 of the arm 87. An arcuate bar 95 is supported on the outer ends of the two arms by means of screw bolts 96 and 97. Near either end of the bar 95 are screw-threaded apertures 98 and 99, and the plate 100 to which the spring 79 is hooked may be changed to either end of the bar 95 and held in place by a screw bolt 101, dependent upon whichever ink fountain is being run. The inside lever 106 has a hub 107 loosely mounted on the shaft 12 within and alongside of the hub 86, and this lever has an arm whose outer end 54 carries the pivoted head 52 which has screw-threaded engagement with the rod 46 as already described. In this form the lever 106 differs from the lever 34 in that it has two roller bearing arms 108 and 108', these arms terminating respectively in yokes 109 and 110 in which are rotatively mounted respectively cam rollers 111 and 112 which cooperate with the cam 16 similarly to the cam roller 31 in the other form. The cam rollers 111 and 112 are brought alternately into operative relation with the cam 16, dependent upon the position of the spring 79 and also upon

whichever of the two inking fountains and fountain rollers are in use. When the roller 111 is in use, the roller x is moved to inoperative position by turning the hand wheel 65, thereby swinging the lever 84 in clockwise position in Fig. 7, the extent of this movement being limited by the stop screw 116 which is screw-threaded into an arm 117 extending laterally from the lower end of the lever arm 84. The stop screw contacts with the back face of the yoke 110 on the arm 108' and limits the outward movement of the upper end 62 of lever 84 and prevents turning hand wheel 65 and bushing 58 off the screw-thread 57.

15 The manner of operation of this form of embodiment will be understood from the statement of operation of the preceding form, the locus and direction of pull of the spring 79 being shifted as already described to bring either the 20 one fountain mechanism or the other into operation.

25 The invention in its broader aspects is not limited to the specific mechanisms shown and described but departures may be made therefrom within the scope of the accompanying claims 25 without departing from the principles of the invention and without sacrificing its chief advantages.

What I claim is:

30 1. A rotary printing press inking mechanism including in combination a fountain roller, an ink drum, a ductor roller and arms on which the ductor roller is mounted, a plurality of levers for rocking the ductor roller and its arms, an actuating cam for one of said levers, an actuating cam for another of said levers, and means for variably angularly positioning one of said levers relatively to the ductor roller arms to govern the dwell of the ductor roller at the fountain roller.

40 2. A rotary printing press inking mechanism including in combination a fountain roller, an ink drum, a ductor roller and arms on which the ductor roller is mounted, a plurality of levers for rocking the ductor roller and its arms, actuating cams for said levers, and means for variably angularly positioning a plurality of said levers relatively to the ductor roller arms.

45 3. A rotary printing press inking mechanism including in combination a fountain roller, an ink drum, a ductor roller and arms on which the ductor roller is mounted, a plurality of levers for rocking the ductor roller and its arms, actuating cams for said levers, and means for simultaneously and equally variably angularly positioning a plurality of said levers relatively to the ductor roller arms.

50 4. A rotary printing press inking mechanism including in combination a fountain roller, an ink drum, a ductor roller and arms on which the ductor roller is mounted, a plurality of levers for rocking the ductor roller and its arms, actuating cams for said levers, and means for variably angularly positioning a plurality of said levers relatively to the ductor roller arms, means for variably angularly positioning one of said levers relatively to said ductor roller arms without disturbing the position of another of said levers relatively to the ductor roller arms.

55 5. A rotary printing press inking mechanism including in combination a fountain roller, an ink drum, a ductor roller and arms on which the ductor roller is mounted, a plurality of levers for rocking the ductor roller and its arms, actuating cams for said levers, and means including a member having screw-threaded engage-

ment with a plurality of said levers for variably angularly positioning a plurality of said levers relatively to the ductor roller arms.

6. A rotary printing press inking mechanism including in combination a fountain roller, an 5 ink drum, a ductor roller and arms on which the ductor roller is mounted, a plurality of levers for rocking the ductor roller and its arms, actuating cams for said levers, and means including a member having screw-threaded engagement with a plurality of said levers for variably angularly positioning a plurality of said levers relatively to the ductor roller arms and means for angularly positioning one of said levers relatively to said ductor roller arms without disturbing the position of another of said levers relatively to the ductor roller arms.

7. A rotary printing press inking mechanism including in combination a fountain roller, an 20 ink drum, a ductor roller and arms on which the ductor roller is mounted, a plurality of levers for rocking the ductor roller and its arms, actuating cams for said levers, and means including a member having screw-threaded engagement with a plurality of said levers for variably angularly positioning a plurality of said levers relatively to the ductor roller arms and screw-threaded means for angularly positioning one of said levers relatively to said ductor roller arms without disturbing the position of another of 30 said levers relatively to the ductor roller arms.

8. A rotary printing press inking mechanism including in combination a fountain roller, an 35 ink drum, a ductor roller and arms on which the ductor roller is mounted, a plurality of levers for rocking the ductor roller and its arms, actuating cams for said levers, and means including a member in fixed angular relation with the ductor roller arms and having screw-threaded engagement with a plurality of said levers for 40 variably angularly positioning a plurality of said levers relatively to the ductor roller arms.

9. A rotary printing press inking mechanism including in combination a fountain roller, an 45 ink drum, a ductor roller and arms on which the ductor roller is mounted, a plurality of levers for rocking the ductor roller and its arms, said levers being mounted concentrically with said arms, actuating cams for said levers, and means for variably angularly positioning a plurality of 50 said levers relatively to the ductor roller arms.

10. A rotary printing press inking mechanism including in combination a fountain roller, an 55 ink drum, a ductor roller and arms on which the ductor roller is mounted, a plurality of levers for rocking the ductor roller and its arms, said levers being mounted concentrically with said arms, actuating cams for said levers, and means for simultaneously and equally variably 60 angularly positioning a plurality of said levers relatively to the ductor roller arms.

11. A rotary printing press inking mechanism including in combination a fountain roller, an 65 ink drum, a ductor roller and arms on which the ductor roller is mounted, a plurality of levers for rocking the ductor roller and its arms, said levers being mounted concentrically with said arms, actuating cams for said levers, and means for variably angularly positioning a plurality of 70 said levers relatively to the ductor roller arms, means for variably angularly positioning one of said levers relatively to said ductor roller arms without disturbing the position of 75

another of said levers relatively to the ductor roller arms.

12. A rotary printing press inking mechanism including in combination a fountain roller, an ink drum, a ductor roller and arms on which the ductor roller is mounted, a plurality of levers for rocking the ductor roller and its arms, actuating cams for said levers, said levers passing successively into operating relation with their respective cams to oppositely move and govern the ductor roller and its arms, and means for variably angularly positioning a plurality of said levers relatively to the ductor roller arms.

13. A rotary printing press inking mechanism including in combination a fountain roller, an ink drum, a ductor roller and arms on which the ductor roller is mounted, a plurality of levers for rocking the ductor roller and its arms, actuating cams for said levers, said levers passing successively into operating relation with their respective cams to oppositely move and govern the ductor roller and its arms, means for variably angularly positioning a plurality of said levers relatively to the ductor roller arms, and means for variably angularly positioning one of said levers relatively to said ductor roller arms without disturbing the position of another of said levers relatively to the ductor roller arms.

14. A rotary printing press inking mechanism including in combination a fountain roller, an ink drum, a ductor roller and arms on which the ductor roller is mounted, a plurality of levers for rocking the ductor roller and its arms, said levers being mounted concentrically with said arms, actuating cams for said levers, said levers passing successively into operating relation with their respective cams to oppositely move and govern the ductor roller and its arms, and means for variably angularly positioning a plurality of said levers relatively to the ductor roller arms.

15. A rotary printing press inking mechanism including in combination a fountain roller, an ink drum, a ductor roller and arms on which the ductor roller is mounted, a plurality of levers for rocking the ductor roller and its arms, said levers being mounted concentrically with said arms, actuating cams for said levers, said levers passing successively into operating relation with their respective cams to oppositely move and govern the ductor roller and its arms, means for variably angularly positioning a plurality of said levers relatively to the ductor roller arms, and means for variably angularly positioning one of said levers relatively to said ductor roller arms without disturbing the position of another of said levers relatively to the ductor roller arms.

16. A rotary printing press inking mechanism including in combination a fountain roller, an ink drum, a ductor roller and arms on which the ductor roller is mounted, a plurality of levers for rocking the ductor roller and its arms, actuating cams for said levers, means for variably angularly positioning a plurality of said levers rela-

tively to the ductor roller arms, and means resiliently impelling said levers toward their cams.

17. A rotary printing press inking mechanism including in combination a fountain roller, an ink drum, a ductor roller and arms on which the ductor roller is mounted, a plurality of levers for rocking the ductor roller and its arms, said levers being mounted concentrically with said arms, actuating cams for said levers, means for variably angularly positioning a plurality of said levers relatively to the ductor roller arms, and means resiliently impelling said levers toward their cams.

18. A rotary printing press having inking mechanism provided with a plurality of fountain rollers and including in combination rotary ink receiving means, means for alternatively vibrating a ductor roller between a selected fountain roller and said ink receiving means comprising a plurality of pivoted actuating levers, 20 rotary cam means cooperating with said levers, and spring means selectively settable to impel a ductor roller towards a selected fountain roller.

19. A rotary printing press having inking mechanism provided with a plurality of fountain rollers and including in combination rotary ink receiving means, means for alternatively vibrating the ductor roller between a fountain roller and said ink receiving means comprising a plurality of pivoted actuating levers, one of said levers having a plurality of arms alternatively cooperating with cam means, rotary cam means cooperating with said levers, and spring means selectively settable to impel a ductor roller towards a selected fountain roller.

20. A rotary printing press having inking mechanism provided with a plurality of fountain rollers and including in combination rotary ink receiving means, a plurality of pairs of arms for mounting ductor rollers, a shaft to which said pairs of arms are fixed, a regulating arm fixed to said shaft, a plurality of actuating levers pivoted on said shaft, means for variably angularly positioning said levers and said regulating arm, cam equipped means for vibrating said actuating levers, one of said levers having a plurality of arms each carrying a cam roller, and spring means settable to impel either one of said arms or the other into operative relation with the cam means.

21. A rotary printing press inking mechanism including in combination a fountain roller, an ink drum, a ductor roller and arms on which the ductor roller is mounted, a plurality of levers for rocking the ductor roller and its arms, means for rocking said levers, means for simultaneously and equally varying the angular relation of said levers to the ductor roller arms, and means for varying the angular relation of one of said levers with respect to another lever and to the ductor roller arms.
